CENTRIFUGAL PUMP AND THE LIKE

Joseph Lichtenstein, Brooklyn, N. Y., assignor to
Foster Wheeler Corporation, New York, N. Y.,
a corporation of New York

Application March 21, 1932, Serial No. 600,085

16 Claims. (Cl. 103—112)

This invention relates to centrifugal pumps and like devices and more particularly to sealing means therefor adapted to handle liquid at high temperatures and high pressures and to balancing means therefor.

The invention is particularly applicable to feed water pumps for supplying water at high temperatures and pressures to a steam boiler. In pumps operating at high temperatures and pressures, as, for example above 500° F. and 1000 lbs. per sq. in., difficulties have been encountered in maintaining leakage through the stuffing boxes at a minimum and in reducing the pressure and temperature at the stuffing boxes to values such that cutting of the packing material or other trouble therewith is not likely to occur.

It is an object of the present invention to provide means for reducing both the temperature and pressure of the water before it is applied to the stuffing box, to a value such that injurious effects are avoided and leakage is reduced to a minimum.

A further object is to reduce the temperature of the water without substantial loss of heat from the system.

A still further object is to provide a sealing means that occupies a minimum amount of axial space in the pump.

Still another and important object of the invention is to eliminate the usual separate balancing disc or device in multi-stage pumps and the accompanying leakage loss due to the flow of water past the balancing disc and back to the suction side of the pump. This I accomplish by my novel construction of sealing means which at the same time serves as a balancing disc.

According to a preferred form of the invention, the high pressure, high temperature leakage water is caused to pass toward the axis of the impeller through a radial labyrinth seal. The centrifugal force produced by the rotation of the water within the labyrinth seal opposes the flow of said water and thereby increases the pressure drop through the labyrinth corresponding to an axial labyrinth of equivalent construction. At its innermost end the labyrinth communicates, with or without additional axial labyrinth passage, with a liquid and vapor separation chamber which is maintained at a low pressure, for example, by a connection to a low pressure operating element of the system in which the pump is used such as a low pressure feed water heater or a condenser. As the pressure of the water is reduced, a portion of the water is vaporized. The heat required to supply the

latent heat of vaporization is extracted from the water itself which is cooled in accordance with established factors of thermodynamics.

The vapor, or steam, is preferably drawn off to a low pressure heater or condenser and the water, which is now at a low temperature and pressure, can be readily handled by a standard stuffing box. The heat of the steam is recovered in the low pressure heater or condenser.

In the preferred form two radial labyrinth 10 discs are employed which are respectively subjected to suction and discharge pressure and which are so dimensioned that the difference in pressure on the two discs balances the unbalanced end thrust due to the pressures on the 15 impellers so that theoretically there is no end thrust in the pump.

Various other features of the invention will be apparent from the following description and accompanying drawings in which a preferred 20 form of the invention is disclosed.

In the drawings:

Fig. 1 is a broken longitudinal sectional view of a centrifugal pump constructed in accordance with the invention;

Fig. 2 is a transverse section taken on the line 2—2 of Fig. 1;

Fig. 3 is a section taken on the line 3—3 of Fig. 1; and

Fig. 4 is a section taken on the line 4—4 of 30 Fig. 2.

Referring more particularly to the drawings, the invention is shown as applied to a centrifugal pump comprising a housing 10 containing a low pressure chamber 11 having an inlet port 12. A 35 shaft 13 is journaled for rotation in said housing and carries a series of impellers 14 which may be of known construction. Guide members 15 and casing parts 17 form channels 18, which direct the liquid from the discharge side of one impeller 40 to the inlet side of the next impeller. Each impeller 14 may be provided with a ring projection 19 which cooperates with a stationary circular groove 20 formed in a section of said housing to restrict flow around the impeller. 45

It is to be understood that the pump may be formed of any number of stages comprising any number of impellers which may be required to build up the desired discharge pressure. The first impeller receives liquid from the low pressure chamber 11. From the last impeller the liquid is discharged into a high pressure chamber 21 formed in housing 10 and communicating with a discharge port 22. 50

On the outside of the last impeller is an in- 55

wardly projecting casing part 30 separated at 31 from the rotor, comprising the shaft and the parts secured thereto. Some of the water leaving the last impeller (the right hand impeller in Fig. 1) passes through the space between this impeller and wall 30 and through space 31 into a circular passage 43 having a plurality of radially extending stationary baffles or ribs 44 therein which may be integral with casing wall 30 and which serve to minimize the rotation of the liquid.

A radially extending labyrinth disc 45 having annular projecting rings 81 thereon is secured to shaft 13 and cooperates with the radial portion of a stationary labyrinth member 46 having annular projecting rings 82 thereon and which is secured to housing 10, to provide a tortuous channel between the interfitting projections 81 and 82 extending in a general radial direction in which the flow of liquid is generally toward the axis of shaft 13. Adjacent labyrinth disc 45 is a sleeve 32 secured on the shaft and having radial projecting rings 33 interfitting between rings 34 on the axially extending portion of member 46 whereby an axial labyrinth is formed as a continuation of the radial labyrinth. The interfitting projections are closely spaced so that the channel between them is narrow. The radial portions of the channels are wider than the axial portions to provide a series of expansion spaces in the labyrinth passage for development of steam. The discharge end 36 of the labyrinth channel communicates with a separation chamber 47 formed in housing 10. Said separation chamber is provided with an outlet port 48 which is connected, as by pipe 49, to a low pressure point such as a feed water heater of the system or a condenser indicated at 80.

The water within flash chamber 47 is held back by a stuffing box comprising a plurality of packing rings 50 of compressible packing material which are held between a projection 51 of housing 10 and a sleeve 52 which is mounted on shaft 13. A gland 53 may be secured to projection 51 in any desired manner for applying longitudinal pressure against said packing rings 50 and maintaining them in operating position. The stuffing box may also be provided with a rigid metallic spacing ring 54 which is located centrally of rings 50. If chamber 47 is operated at a pressure below atmospheric, water under pressure may be supplied through a pipe 56 to the space adjacent ring 54 to form an air seal for preventing air from being drawn into chamber 47 through the stuffing box.

The sealing means for the low pressure side of the pump is similar to that described above and, although the following description thereof is less detailed, it is to be understood that the various parts correspond in construction and function. Low pressure chamber 11 communicates by means of a passage 59 with a circular passage 63 containing a plurality of radially extending stationary baffles or ribs 64 which are formed similar to the baffles 44 at the high pressure end of the pump. A radial labyrinth seal comprising a rotating radial labyrinth disc 66 and an axial labyrinth sleeve 69 mounted on shaft 13 and stationary labyrinth member 67 secured in housing 10 is located between circular passage 63 and a separation chamber 65. These parts have intermeshing projections and form a tortuous passage having a radial inwardly extending portion and an axial portion similar to that at the high pressure end. Said chamber 65

is provided with an outlet port 37 which may be connected as by pipe 37 to a suitable low pressure point 80. Chamber 65 is sealed by a stuffing box comprising a plurality of packing rings 68 held between projection 69 of housing 10 and a sleeve 70 carried on shaft 13. Said packing rings are held in position by gland 71 in any well known manner. A metallic spacing ring 72 may be located centrally of rings 68 and a connection 74 may be provided for applying water for sealing 10 against vacuum.

The operation of the above described sealing means is as follows, referring to the sealing means at the high pressure end:

The leakage water at high temperature and 15 high pressure passes between the right hand impeller 14 and wall 30 and thence through circular passage 43 wherein ribs 44 substantially prevent the water from rotating. From passage 43 the water passes through the radial labyrinth passage 20 formed by disc 45 and the radial portion of member 46 and is caused to travel toward the axis of shaft 13. The movement of rotating disc 45 causes the water flowing through the tortuous passage to rotate and to thereby set up outwardly directed centrifugal force which opposes the inward passage of the water therethrough. This centrifugal force introduces a resistance to the flow of water equivalent to the resistance of a considerable number of labyrinth turns. There 30 is a continuously decreasing pressure gradient through the labyrinth seal and steam is flashed from the water therein as the water flows therethrough. After reaching the inner end of the radial portion of the labyrinth passage, the fluid 35 then being a mixture of water and steam, passes through the generally axial portion of the labyrinth passage between member 32 and projection 34. The steam and water mixture after passing 40 through the labyrinth passage enters separation chamber 47 which is maintained at suitable low pressure such as atmospheric or somewhat above or below atmospheric, depending upon the low pressure point to which pipe 49 is connected. In passing through the labyrinth passage, the hot 45 water is reduced in pressure and some of it is flashed into steam, the latent heat of vaporization being taken from the liquid. The temperature of the leakage liquid is thus reduced correspondingly to the reduction in pressure. Chamber 50 47 accordingly receives a mixture of water and steam, preferably at a temperature not materially exceeding 212° F. The steam is withdrawn to the low pressure point through pipe 49 and the water which is now at low pressure 55 and temperature is readily held back by the stuffing box and the temperature and pressure is such that the stuffing box can stand up.

The above described method of flashing for sealing purposes has the further advantage of 60 reducing the amount of leakage considerably. As soon as the pressure drop in the first labyrinth turns has been sufficient to reduce the pressure of the hot water below the corresponding temperature of the water, flashing starts and the mixture of steam and water flows through the 65 succeeding turns while more steam is flashed. It can readily be seen that the lower the pressure becomes the bigger the volume of the steam becomes as compared to the initial volume of the water entering the labyrinth system. Since at the same time the cross-sectional area of the 70 passage becomes smaller in the radial portion of the labyrinth and at least does not increase in the axial portion, the velocity of the mixture 75

must increase enormously, or the amount of the mixture for a given pressure drop is correspondingly decreased.

If chamber 41 is maintained at a pressure below atmospheric, access of air thereto may be prevented by applying water under pressure to pipes 56 and 74.

The operation of the low pressure end sealing means is the same as that at the high pressure end.

Besides serving to provide a radial flow labyrinth, the member 45 serves also as a balancing disc. The pump has an end thrust due to the impellers toward the low pressure end. This is offset because the pressure differential on the two sides of disc 45 is greater than the pressure differential on the two sides of disc 66. Consequently there is an unbalanced thrust on the labyrinth discs which acts oppositely to the unbalanced thrust of the impellers. The labyrinth discs can be designed with respect to area so as to equalize the thrust of the impellers. Therefore it may be said that the labyrinth disc permits the omission of the usual balance disc and connection from the high pressure end to the low pressure end, with corresponding saving of leakage flow between these two points.

I have shown a combined radial flow and axial flow labyrinth because the pump shown was designed for service in which the placing of the entire labyrinth passage radially would have necessitated a disc of such radial extent as to give rise to undesirable rotational strains. It will be appreciated nevertheless that there are great advantages in the radial flow labyrinth whether or not combined with an axial labyrinth. The equivalent entire axial labyrinth passage to what is shown in Fig. 1 would make a much longer pump. The effects of centrifugal flow opposition and balancing are not present in an axial labyrinth.

By the use of radially extending labyrinth seals in which centrifugal force is utilized to impede the flow of the leakage water, any desired number of labyrinth may be employed to obtain the necessary pressure drop without materially increasing the axial length of the pump. It will be understood that a number of radial flow labyrinth channels in accordance with the invention can be connected in series. It is obviously a matter of design whether to use one or several radial labyrinth or whether to combine an axial labyrinth with one or more radial labyrinth.

By converting a portion of the leakage water into steam and using the latent heat of vaporization thereof for cooling purposes, a comparatively great cooling effect is obtained and at the same time loss of heat in the system is avoided, since the heat value may be recovered therefrom in the feed water heaters or other devices. The system is accordingly particularly efficient from the standpoint of heat loss and may be so designed that the temperature and pressure of the leakage water may be reduced to any desired value before the water is applied to the stuffing box. This permits the stuffing boxes to be used for considerable periods of time without injury and materially reduces both the cost of installation and the maintenance charges of the pump.

Although a preferred form of the invention has been shown and described for purposes of illustration, it is obvious that various modifications and changes may be made therein. For example, the packing herein described may be applied to various other utilities wherein high pressures

and high temperatures are involved, such as in special liquid pumps and in turbines. It will be appreciated that the novel balancing feature is applicable to pumps with different kinds of sealing means or different paths of flow of liquid. Various specific terms have been used in the present description for convenience and not by way of limitation. The invention is only to be limited in accordance with the following claims when interpreted in view of the prior art.

What I claim is:

1. In a device adapted to operate with liquids at high pressure, a rotor and a housing, a stuffing box carried by said housing and cooperating with said rotor, a passage having radial baffles therein and adapted to have radial flow of liquid therein toward the periphery thereof, fixed and rotatable members forming a radial labyrinth seal communicating at its outer end with said passage and adapted to have radial flow of said liquid through said labyrinth toward the axis of said rotor and causing rotational flow of said liquid about said axis whereby centrifugal force is developed to oppose said flow, and a chamber for receiving the liquid after passage through said radial labyrinth seal and in communication with said stuffing box.

2. In a device adapted to operate with liquids at high pressure, a rotor and a housing, a stuffing box carried by said housing and cooperating with said rotor, and means to reduce the temperature and pressure of the liquid within said housing before applying the same to said stuffing box comprising a circular passage formed in said housing to receive leakage liquid, stationary baffles in said passage to substantially prevent rotation of liquid therein, a radial flow tortuous labyrinth passage having its outer end communicating with the periphery of said passage, and means for causing passage of said liquid through said labyrinth passage toward the axis of said rotor while rotating about said axis whereby centrifugal force is produced for opposing the flow of liquid comprising a low pressure separation chamber connected to receive liquid from said labyrinth at a point near the axis of said rotor, whereby to vaporize a portion of said liquid and to reduce the temperature of the remaining liquid.

3. A centrifugal pump comprising a housing, a rotor, a passage in the housing adapted to receive leakage liquid, a rotating disc one side of which forms a wall of the passage, and means in the passage to reduce the rotation of the liquid leaking thereinto, the other side of the disc having projections forming, with a cooperating member, a labyrinth seal.

4. A centrifugal pump comprising a housing, a rotor, a passage in the housing adapted to receive leakage liquid, a rotating disc one side of which forms a wall of the passage, means in the passage to reduce the rotation of the liquid leaking thereinto, the other side of the disc having projections forming, with a cooperating member, a radially extending labyrinth seal, and an axially extending labyrinth seal communicating with the radially extending labyrinth seal.

5. A centrifugal pump comprising a housing, a rotor, a passage in the housing adapted to receive leakage liquid, a rotating disc one side of which forms a wall of the passage, means in the passage to reduce the rotation of the liquid leaking thereinto, the other side of the disc having projections forming, with a cooperating member, a radially extending labyrinth seal, an axially extending labyrinth seal communicating

with the radially extending labyrinth seal, a chamber in the housing adapted to receive the liquid leaking from the axially extending labyrinth seal, a stuffing box communicating with the chamber, and means for partially vaporizing the liquid in said chamber to cool the remaining liquid and thereby cool the stuffing box.

6. Apparatus for pumping liquids comprising stationary and movable members, a stuffing box between said members, means causing leakage liquid to flow into contact with the stuffing box, and means including a source of pressure outside the stationary member for subjecting the leakage liquid to a pressure lower than the pressure at which the liquid will vaporize at the temperature thereof, whereby the ensuing vaporization will cool the remaining leakage liquid and the stuffing box.

7. Apparatus for pumping relatively high temperature liquids comprising stationary and movable members, a stuffing box between said members, means causing leakage liquid to flow into contact with the stuffing box, and means including a source of pressure outside the stationary member for subjecting the leakage liquid to a pressure substantially lower than the pressure at which the liquid will vaporize at the temperature thereof, whereby the ensuing vaporization will cool the remaining leakage liquid and the stuffing box.

8. Apparatus for pumping liquids comprising stationary and movable members, a stuffing box between said members, means causing leakage liquid to flow into contact with the stuffing box, and means including a source of pressure outside the stationary member for subjecting the leakage liquid to a pressure lower than the pressure at which the liquid will vaporize at the temperature thereof, whereby the ensuing vaporization will cool the remaining leakage liquid and the stuffing box, said last mentioned means serving to conduct the vapor evolved from the apparatus.

9. Apparatus for pumping liquids comprising stationary and movable members, a stuffing box between said members, means including a restricted passageway for causing leakage liquid to flow into contact with the stuffing box, and means including a source of pressure outside the stationary member for subjecting the leakage liquid to a pressure lower than the pressure at which the liquid will vaporize at the temperature thereof, whereby the ensuing vaporization will cool the remaining leakage liquid and the stuffing box.

10. Apparatus for pumping liquids comprising stationary and movable members, a stuffing box between said members, a chamber in communication with the stuffing box, means causing leakage liquid to flow into the chamber and into contact with the stuffing box, and means including a source of pressure outside the stationary member for subjecting the leakage liquid flowing into the chamber to a pressure lower than the pressure at which the liquid will vaporize at the temperature thereof, whereby the ensuing vaporization will cool the remaining leakage liquid and the stuffing box.

11. Apparatus for pumping liquids comprising stationary and movable members, a stuffing box between said members, a chamber in communication with the stuffing box, means causing leakage liquid to flow through a restricted passage into the chamber and into contact with the

stuffing box, and means including a source of pressure outside the stationary member for subjecting the leakage liquid flowing into the chamber to a pressure lower than the pressure at which the liquid will vaporize at the temperature thereof, whereby the ensuing vaporization will cool the remaining leakage liquid and the stuffing box.

12. Apparatus for pumping liquids comprising stationary and movable members, a stuffing box between said members, a chamber in communication with the stuffing box, means causing leakage liquid to flow through a restricted passage into the chamber and into contact with the stuffing box, and means including a source of pressure outside the stationary member for subjecting the leakage liquid flowing into the chamber to a pressure lower than the pressure at which the liquid will vaporize at the temperature thereof, whereby the ensuing vaporization will cool the remaining leakage liquid and the stuffing box, said last mentioned means serving to conduct the evolved vapor to the source of the lower pressure.

13. A centrifugal pump comprising a rotor and a housing, a stuffing box carried by the housing and cooperating with the rotor, means causing leakage liquid to flow into contact with the stuffing box, and means including a source of pressure outside said housing for subjecting the leakage liquid to a pressure lower than the pressure at which the liquid will vaporize at the temperature thereof, whereby the ensuing vaporization will cool the remaining leakage liquid and the stuffing box.

14. A centrifugal pump comprising a rotor and a housing, a stuffing box carried by the housing and cooperating with the rotor, means causing leakage liquid to flow through a restricted passage into contact with the stuffing box, and means including a source of pressure outside said housing for subjecting the leakage liquid to a pressure lower than the pressure at which the liquid will vaporize at the temperature thereof, whereby the ensuing vaporization will cool the remaining leakage liquid and the stuffing box.

15. A centrifugal pump comprising a rotor and a housing, a stuffing box carried by the housing and cooperating with the rotor, a chamber in communication with the stuffing box, means causing leakage liquid to flow into the chamber and into contact with the stuffing box, and means including a source of pressure outside said housing for subjecting the leakage liquid flowing into the chamber to a pressure lower than the pressure at which the liquid will vaporize at the temperature thereof, whereby the ensuing vaporization will cool the remaining leakage liquid and the stuffing box.

16. A centrifugal pump comprising a rotor and a housing, a stuffing box carried by the housing and cooperating with the rotor, a chamber in communication with the stuffing box, means causing leakage liquid to flow through a restricted passage into the chamber and into contact with the stuffing box, and means including a source of pressure outside said housing for subjecting the leakage liquid flowing into the chamber to a pressure lower than the pressure at which the liquid will vaporize at the temperature thereof, whereby the ensuing vaporization will cool the remaining leakage liquid and the stuffing box.

JOSEPH LICHTENSTEIN.
